UNITED STATES PATENT OFFICE.

BERT G. DUNHAM, OF HAWTHORNE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 16, 1925. Serial No. 62,725.

This invention relates to telephone exchange systems for interconnecting subscribers at manual and automatic offices, and more particularly to systems of the step-by-step type.

The object of the invention is the provision of improved cordless "B" circuits whereby an operator at a manual office is connected to a cordless "B" operator in an automatic office who receives the number to which connection is desired directly over the trunk to the manual office, and controls the setting of switches in which the trunk terminates to establish the connection.

15 A feature of the invention is the provision of a counting relay arrangement employing a smaller number of pairs of relays than the maximum number of impulses to be counted, including optional pairs of relays and 20 means for choosing between said optional pairs dependent upon the number of impulses to be counted.

25 A further feature of the invention is the employment of the sender circuit as either a four digit or a five digit sender. The sender circuit is provided with a relay which is operated if the first or thousands digit has certain numerical values to delay the disconnection from the link circuit until 30 after a fifth digit has been registered and sent. If this relay is not operated the sender is dismissed after the sending of four digits.

35 A further feature of the invention lies in the provision of means for restoring the sender to normal and resetting the registers without disconnecting the sender from the link. This method of control makes it possible for the "B" operator to reset the registers in case a mistake has been made in setting up one or more of a series of digits.

40 A further feature of the invention is the combination link and control circuit to establish a straightforward trunking circuit between "A" and "B" operator's positions 45 as well as to establish switch control circuits from the sender to switches associated with the trunk.

50 Fig. 1 shows diagrammatically a calling subscriber's substation connected to an answering jack and a cord circuit at an "A" operator's position in a manual office, and

further shows in detail an outgoing trunk jack associated with a trunk circuit in the called office, also the first selector of the called office enclosed by the broken line. 55

Figs. 2, 4 and 5 show the link circuit comprising a trunk finder circuit (Fig. 2), a position selector (Fig. 5), and a sender selector (Fig. 4).

Fig. 3 shows a position circuit for a cordless "B" operator to enable such operator to talk with the manual "A" operator over a connection established through the link circuit, and to set the selected sender by means of a keyboard sender. 60

65 Figs. 6, 7 and 8 constitute the "B" operator's sender circuit, Fig. 6 showing the transfer relays, Fig. 7 the register relays, and Fig. 8 the six pairs of counting relays. Fig. 9 shows the relative positions of drawings 1 to 8. 70

The system disclosed as embodying the present invention will be best understood from a description of the operation thereof taken in conjunction with the accompanying drawings. 75

A manual subscriber 100 upon lifting the receiver from the hook lights a line lamp at the "A" operator's position in the well known manner whereupon the "A" operator 80 plugs into the answering jack and receives the number desired. The "A" operator by means of her cord circuit 103 connects the manual calling subscriber 100 to a trunk outgoing to the called office by plugging into 85 outgoing trunk jack 104. When the manual operator plugs into the jack 104 associated with trunk conductors 105 and 106, relay 107 operates over the trunk loop in a circuit which may be traced from ground through 90

the right winding of relay 107, right back contact of relay 109, right normal contact of relay 110, upper left winding of repeating coil 111 to the tip of jack 104, tip of plug 112 through the usual polarized relay (not shown) of the cord circuit 103, ring of plug 112 and jack 104, conductor 106 through the lower left winding of repeating coil 111, left normal contact of relay 110, left back contact of relay 109, left winding of relay 107 to battery. The operation of relay 107 in turn operates relay 108 in a 95 100

circuit from ground at the right front contact of relay 107 through the winding of relay 108 to battery and ground.

The operation of relay 108 closes the circuit for starting the trunk finder by connecting ground to group start lead 113. Relay 200 operates in a circuit which may be traced from ground at the right back contact of relay 114, right front contact of relay 108, conductor 113, through normally closed group start key 201, winding of relay 200, right back contact and armature of relay 218 to grounded battery. Relay 200 operated connects ground to commutator segment 115 corresponding to the level in which the trunk appears. The apparatus within the dotted rectangle of Fig. 2 is a part of the trunk circuit. Relay 202 operates in a circuit which may be traced from battery in the alarm circuit, right winding of relay 202, middle left back contact of relay 210, middle right back contact of relay 442, upper normal contact of key 240, to ground at the right contact of relay 200.

Relay 202 operated closes an operating path for relay 203 which may be traced from grounded battery, right winding of relay 203, armature and closed contact of rotary magnet 208, closed contact and armature of vertical magnet 206, conductor 228, contact of relay 202 to grounded contact of relay 210. Relay 202 operated also closes a start lead to the link circuit at its middle front contact, and opens a short circuit between leads 204, 205 at its outermost left back contact. Relay 203 operated energizes the vertical magnet 206 in a circuit which may be traced from grounded battery through the winding of vertical magnet 206, left back contact of relay 207 to grounded contact of relay 203. The trunk finder switch takes one vertical step, thus breaking the energizing path for relay 203. Relay 203 will accordingly release and allow vertical magnet 206 to release as well. Magnet 206 having released, relay 203 will again energize and the trunk finder switch will take another vertical step. This action will continue until the commutator brush 116 connects to grounded commutator segment 115. Relay 203 will be held operated and relay 207 will operate in a circuit which may be traced from grounded battery through the right winding of relay 203, armature and contact of rotary magnet 208, conductor 209, left winding of relay 207, next to the innermost left back contact of relay 210, conductor 230, commutator brush 116, commutator segment 115, conductor 231 to ground at the left front contact of relay 200. The operation of relay 207 opens the energizing circuit of vertical magnet 206 allowing it to release, and causes rotary magnet 208 to operate in a circuit which may be traced from grounded battery through the winding of rotary magnet 208, conductor

232, left front contact and armature of relay 207 to grounded contact of relay 203. The trunk finder switch thereupon takes one rotary step. Rotary magnet 208 causes relay 203 to function the same as did vertical stepping magnet 206 and the switch will continue to take rotary steps until the transfer conductor 211 connects to the contact which is connected to battery through relay 109 of the trunk circuit. Thereupon relay 203 will be held energized in a circuit which may be traced from ground through the left winding of relay 210, through the left winding of relay 203 in series, outer front contact of relay 202, conductor 211, brush 235, contact 118, test conductor 117, left back contact of relay 114, left contact of relay 108, winding of relay 109 to grounded battery. Relay 210 will energize in this circuit and lock to ground through the off-normal contact 212 in a circuit which may be traced from grounded battery through the right winding of relay 210, left front contact of that relay, to ground at off-normal contact 212. The operation of relay 210 will connect direct ground from the innermost grounded armature of that relay to test lead 211 and will open the energizing circuit of relay 207 at its left innermost back contact. Relay 207 releases and extends the start circuit to the next idle trunk finder. The extended start circuit may be traced from ground at the right contact of relay 200, intermediate normal contact of key 240, middle right back contact of relay 442, middle left front contact of relay 210, right back contact of relay 207, inner right back contact of relay 442, upper normal contact of key 240 thence to the out start wire connected to this contact of key 240. Relay 210 operated closes a circuit for operating relay 213 which may be traced from grounded battery through the winding of relay 213, innermost front contact of relay 202 to the intermediate grounded armature of relay 210. The operation of relay 210 also opens the commutator brush circuit traced hereinabove and closes a chain relay circuit at its left front innermost contact and armature which forms a part of an all-finders-busy circuit. The operation of relay 213 at this time connects the talking leads of the trunk through to the link, closes the pulsing leads over which the switches are to be operated in reaching the wanted number, opens the release magnet circuit and partially closes a short circuiting path across leads 204, 205 at its lowermost front contact.

When the trunk finder finds the trunk, relay 109 operates in a circuit which may be traced from grounded battery, winding of relay 109, conductor 119, left contact of relay 108, left back contact of relay 114, test conductor 117, test contact 118, test brush 235, conductor 211, outermost front contact 130

of relay 202, innermost grounded contact of relay 210. The operation of relay 109 causes the release of relays 107 and 108. Relay 109 operated, locks to test lead 117 in a circuit which may be traced from grounded battery, winding of relay 109, left front contact of relay 109, conductor 120, left back contact of relay 114 to ground on test lead 117.

As soon as the trunk finder switch took one step, relay 400 was operated in a circuit which may be traced from grounded battery, winding of relay 400, conductor 402, off-normal contact 229 to ground at next to the outermost left back contact of relay 210. The operation of relay 400 causes relay 401 to operate in an obvious circuit.

When relay 213 operated as above described, extending the talking conductors through to the link circuit, relay 431 operated in a circuit from battery, left winding of relay 431, outer left back contact of relay 439, left normal contact of relay 437, conductor 205, innermost upper contact of relay 213 through the trunk finder, conductor 106, ring of jack 104 and plug 112, through the usual polarized relay (not shown) of the "A" operator's cord circuit, tip of plug 112 and jack 104, conductor 105, through the trunk finder, next to the innermost upper contact of relay 213, conductor 204, right normal contact of relay 437, right winding of relay 431 to ground. The operation of relay 210 opened the energizing circuit of relay 400, but relay 400, being slow-to-release, remains energized long enough for relay 431 to operate and close a locking circuit for relay 400 over its left front contact to ground at the front contact of relay 400. Relay 400 holds relay 401 operated. Since the operation of relay 401 is necessary to close switch setting conductor 233, the extension of the connection is now in part under the control of the "A" operator.

When relay 202 operated to start the trunk finder, relay 403 operated in a circuit which may be traced from grounded battery, through winding of relay 403, conductor 236, front contact and grounded armature of relay 202, closing the position finder start circuit. Relay 500 operates in a circuit which may be traced from grounded battery, winding of relay 500, conductor 532, normally closed contact of relay 529, conductor 533, right back contact of relay 520, left back contact of relay 508, conductor 534, left middle contact of relay 403, conductor 352 to ground in the position circuit. Operated relay 500 connects ground from its right contact to the winding of relay 501 which thereby energizes. Relay 501 operated closes an energizing circuit for operating stepping magnet 502 of the position finder which may be traced from grounded battery, winding of stepping mag-

net 502, conductor 536, normally closed contact of relay 508, conductor 537, contact and armature of magnet 404, conductor 538, contact of stepping magnet 502, winding of relay 503, inner right contact of relay 501, conductor 539 to ground at the inner left contact of relay 403. Relay 501 operated thus closes a path for operating relay 503 and prepares a locking path for relay 504 over its left front contact to ground at the back contact of relay 505. If the terminal on which the test brush 527 of the position finder is resting is grounded indicating that the position is busy or vacant, a shunt is closed around the winding of relay 503 extending over the outer right contact of relay 501, left back contact of relay 503, inner right back contact of relay 509, brush 527, to grounded conductor 507. The stepping magnet 502 will operate its armature and interrupt its own circuit causing the switch brushes to advance one step. This action will continue until an idle terminal is found. When an idle terminal is found, relay 503 will operate from battery through the stepping magnet in the circuit hereinabove traced, close a testing circuit for relay 505 through to lead 506. Relay 503 operated, also grounds test lead 507 and closes a path for operating relay 504. Under this condition if there is only one switch testing a terminal, relay 505 will operate to open the path for operating relay 504. Relay 505 operated, operates relay 508 in a circuit which may be traced from grounded battery, winding of relay 508, right outer back contact of relay 509, conductor 540, front contact of relay 505 to ground. The operation of relay 508 opens the energizing circuit for relay 500 which will restore to normal, causing relays 501 and 503 to release, thus opening the energizing circuit for relay 505. The deenergization of relay 505 opens the circuit for energizing relay 508. Under this condition, relay 508 will lock through its left middle contact, the winding of relay 509, conductor 539 to ground at the innermost left contact of relay 403. Relay 509 is energized in this circuit and will in turn operate relay 510 in a circuit which may be traced from grounded battery, winding of relay 510 through the left front contact of relay 509, conductor 541, right back contact of relay 405, outer left back contact of relay 406, conductor 407, middle contact of relay 401, inner right contact of relay 403, conductor 237 to the middle grounded armature of relay 210. Relay 508 operated, connects the guarding ground to test brush 527 of the position finder in a circuit which may be traced from ground, right middle contact of relay 403, conductor 408, right back contact of relay 542, conductor 409, back contact of relay 406, conductor 543, left contact of relay 508, to test brush 527. Relay 508 oper-

ated, connects, through its right front contact, stepping magnet 404 of the sender selector to the relays which control the operation thereof. Relay 509 operated, transfers the lead 540 to relay 511 and connects the test brush 414 through to the relays which control the operation of the sender selector. Relay 510 operated, transfers the test circuit from lead 506 of the position selector to lead 419 of the sender selector over its outer right front contact. It also closes the talking leads 514 and 515 to the "B" operator's position (Fig. 3) and closes the start lead 416 to relay 500.

This start circuit for relay 500 may be traced from battery through the winding of relay 500, right normal contact of relay 529, inner right front contact of relay 510, right inner contact of relay 511, conductor 416, through the right contact of key 805, to ground at the right back contact of relay 802 of any idle sender in the group. As before, relay 500 operates relay 501 and relay 501 closes the circuit for the sender selector magnet 404.

The circuit of the sender selector stepping magnet 404 may be traced from battery through the winding of the magnet, right alternate contact of relay 508, back contact of magnet 404, back contact of magnet 502, and thence in parallel through the winding of relay 503 to grounded conductor 539 and over the outer right front contact of relay 501, left back contact of relay 503, inner right front contact of relay 509, to conductor 417, brush 414, conductor 415, left contact of key 805, to the front contact of relay 807 which will be operated if the sender is busy. In the case of a busy sender, however, relay 503 is shunted as in the case of a busy position and magnet 404 operates, opening its own circuit and advancing the sender selector to the next sender. When an idle sender is found relay 807 will not be operated and no shunt will be closed around the winding of relay 503. Relay 503 in operating connects ground over its inner left front contact, to brush 414 to mark the sender busy to other sender selectors.

Relay 503 will also close a circuit from ground at the back contact of relay 504 through the winding of relay 505, outer right front contact of relay 503, outer left front contact of relay 510, inner right normal contact of relay 511, conductor 419, brush 427, conductor 418, right back contact of relay 802, resistance 880 to battery. Relay 505 operates in this circuit and closes a circuit from battery through the winding of relay 511, outer right front contact of relay 509 to ground at the front contact of relay 505. Relay 511 operates and closes a locking circuit for itself over its outer left contact, winding of relay 517 to grounded conductor 408. As before the operation of relay 503 closed a circuit for slow-to-operate relay 504

which when it operates opens the circuit of relay 505 which when it operates opens the circuit for relay 504. The operation of relay 511 as previously described opens the circuit of relay 500, restoring that relay and relays 501 and 503 to normal. The release of relay 505 when its circuit is opened by slow-to-operate relay 504, opens the energizing circuit of relay 511 permitting relay 517 to operate in the locking circuit of relay 511.

Relay 410 now operates in a circuit which may be traced from grounded battery through winding of relay 410, conductor 411, outermost left armature and front contact of relay 517, conductors 545, 408 and 412, right middle front contact of relay 403 to ground. Relay 511 operated, grounds the test lead 417 in the sender selector and closes an additional locking circuit for locking relays 511 and 517 in series, which circuit may be traced from grounded battery, through winding of relay 511, outer left front contact of relay 511, conductor 544, winding of relay 517, outer left front contact of relay 517, conductor 411, left front contact of relay 410, conductors 413, 408 and 412 to the middle right front contact of relay 403. Relay 511 operated also opens the start lead and the circuit of the control relays of the sender selector at its outermost right armature and prepares a circuit for relay 520 which may be traced from grounded battery, right back contact of relay 546, conductor 547, winding of relay 520, inner left front contact of relay 511, conductor 548, to ground at the outer back contact of relay 410. Relay 517 operated connects leads 521, 506 and 522 from the position finder to the corresponding leads 419, 420 and 461 from the sender selector. Relay 410 operated connects the pulsing leads 233, 234 from the trunk finder (Fig. 2) to the sender selector pulsing leads 421 and 422. Relay 410 operated, also opens its left and right outermost contacts for controlling relay 520 and locks to the control ground supplied by relay 403.

When the "B" position is seized relay 300 will operate in a circuit which may be traced from ground at the outer left back contact of relay 549, conductor 550, left winding of relay 542, middle left front contact of relay 510, position finder brush and contact 551, conductors 515 and 310 through the winding of relay 300, conductors 311 and 514 to the contact and brush 552 of the position finder, outermost left front contact of relay 510, right winding of relay 542 to grounded battery. Relay 300 operated, operates relay 301 in a circuit which may be traced from grounded battery through the winding of relay 301 to ground at the right front contact of relay 300.

When the "B" operator inserted her headset plug into jacks 313 and 380 a circuit was closed from battery through the winding of

relay 350, tip of jack 380, through the telephone headset, tip of jack 313, right winding of induction coil 351 to ground. The operation of relay 350 disconnects the ground which marks the position vacant from the test lead 507. It also prepares a test circuit from conductor 507, over its left front contact, and connects ground over its right front contact, right back contact 5 of relay 301 to conductor 352 for the purpose previously set forth. When now the position finder connects with the position and relay 508 operates connecting ground to brush 527, a circuit is closed from battery through the winding of relay 314, right back contact of relay 353, left front contact of relay 350, conductor 507, to ground at brush 527. Relay 314 in operating supplies ground to the numerical keys and other 10 parts of the circuit for controlling the position apparatus. It also closes an obvious circuit for operating relay 354. With relays 301 and 354 operated, lamps 302 and 303 are lighted, lamp 302 over the inner right front contact of relay 354 and the outer left front contact of relay 301 to ground; lamp 303 over the right back contact of relay 319 and the left back contact of relay 306 to ground at the outer right contact of relay 354. The lighting of these 15 lamps identifies the trunk over which the call is incoming.

Relay 354 also closes an operating circuit for relay 353 extending through the winding of that relay, left front contact of relay 354, outer right front contact of relay 301 to ground at the right contact of relay 350. The operation of relay 353 disconnects relay 314 from the test lead 507 but relay 314 is held operated by ground over the inner left contact of relay 301. Relay 353 connects ground over its outer right front contact to test lead 507 to mark the position busy. It also closes a locking 20 circuit for itself to ground over its middle right contact and the left contact of relay 354. Over its inner right contact relay 353 connects ground through the winding of relay 355 to battery at the left normal contact of relay 356.

This position circuit is arranged to transmit two short impulses of tone to the "A" operator to notify her that the "B" operator is ready to receive the number. The first tone is transmitted as soon as relay 301 operates due to the closure of a circuit from source of tone over the inner right front contact of relay 301, back contact of relay 357, right back contact of relay 358, lower winding of repeating coil 359 to ground. This induces the tone in the upper winding of repeating coil 359 which is transmitted over the back contact of relay 356 to conductors 514 and 515 and the "A" operator's position. The operation of re-

lay 355, which is described above, closes a locking circuit for itself from battery over its right alternate contact and also closes a circuit from battery over the normal contact of relay 356, left back contact 70 of relay 357, winding of relay 358 to ground at the left contact of relay 355. As soon as relay 358 operates it opens the tone circuit and the tone ceases in the "A" operator's headset. It also closes a circuit from battery over its right alternate contact through the winding of relay 357 to ground at the left contact of relay 355. Relay 357 locks over its inner left front contact, to battery at the normal contact of relay 356 75 80 and opens the energizing circuit of relay 358. When relay 358 closes its back contact, a circuit is again closed from the source of tone, this time over the right front contact of relay 357, left contact of relay 358, lower winding of repeating coil 359, to ground and a second tone is transmitted to the "A" operator.

The release of relay 358 with relay 357 operated closes a circuit from battery over 90 the right normal contact of relay 358, outer left front contact of relay 357, winding of relay 356 to ground at the left contact of relay 355. Relay 356 closes a locking circuit for itself over its left alternate contact 95 and connects the talking conductors 515 and 514 through to the "B" operator's headset. Relay 356 is slow-to-operate and does not cut off the tone until after a measured interval. The slow release and slow operating character of relays 356, 357 and 358 serves the purpose of measuring the length of the tone and the interval between tones.

When the pulsing leads where connected through to the sender by the operation of relay 410 as previously described a circuit was closed from battery through the winding of relay 151 in the first selector, inner left back contact of relay 152, conductor 153, through the trunk finder, next to the 100 uppermost front contact of relay 213, conductor 234, middle right contact of relay 410, conductor 421, through the sender selector to conductor 425, winding of relay 881, outer right back contact of relay 809, inner 105 right back contact of relay 825, conductor 426, through the sender selector, conductor 422, inner right front contact of relay 410, inner right front contact of relay 401, conductor 233, uppermost contact of relay 213, 110 through the trunk finder, conductor 154, outer left back contact of relay 152, left winding of relay 151, contact 155 to ground. Relay 881 operates in this circuit and closes 115 an obvious circuit for operating relay 882.

Relay 882 in turn operates and closes an obvious circuit for relay 803. Relay 803 in operating connects battery over its left front contact to the register relays, and connects ground over its right front contact 120 125 130

and the back contact of relay 809, to complete the holding circuit of certain relays as will hereinafter appear. It also closes an obvious circuit for operating relay 807. Relay 807 connects ground over its right front contact and the left contact of key 805 to test lead 415 marking the sender busy. It also closes an obvious circuit for relay 802 which disconnects ground from conductor 416 and disconnects battery from conductor 418. At its right front contact relay 802 connects conductor 418 to relay 883. As soon as relay 803 operated, connecting ground to conductor 610, relay 600 operated in a circuit from battery through its winding, outer left back contact of relays 603, 604, 605, 606 and 608, conductor 609 to grounded conductor 610. With relay 600 operated, a circuit is closed from battery over the left front contact of relay 803, conductor 612, through the right winding of relay 613, outer right front contact of relay 600, conductor 620, winding of relay 884, conductor 424, sender selector brush 429, conductor 461, inner left front contact of relay 517, position selector brush 558, conductor 522, outer left back contact of relay 305, winding of relay 304, conductor 315, right back contact of relay 316, normal contact of relay 318 to ground at the right front contact of relay 314.

Relay 304 operates in this circuit but relays 613 and 884 do not. Relay 304 closes a circuit from grounded conductor 315 over its front contact, left back contact of relay 319, winding of relay 306 to battery. Relay 306 operates and locks over its inner left contact to grounded conductor 315. The operation of relay 306 extends conductor 506 to the numerical keys. It also closes a circuit from battery through the winding of relay 305, middle left contact of relay 306 to grounded conductor 315. In addition it opens the circuit of the white lamp 303 indicating to the "B" operator that the sender is ready to receive registrations. The operation of relay 305 extends conductors 521 and 522 through to the numerical keys. It may be noted that conductors 522 and 521 are extended through resistance coils so as to compensate for the presence of relay 555 in conductor 506. The operation of relay 305 opens the circuit of relay 304 and that relay releases. When the "B" operator presses the numerical keys corresponding to the number given her by the "A" operator, she will connect direct ground or ground through resistances 321 and 322 to leads 506, 521 and 522 dependent on which keys are pressed.

Following is a table indicating the relationship between the keys of the "B" operator's key set, the conductor to which ground is applied and the nature of that ground (whether direct or through a resist-

ance), and the relay or relays operated thereby in the first register. The relays of the various registers are similarly located, so that the correspondence between a key and the proper relay of a particular register 70 may easily be determined.

Key.	Conductor.	Resistance.	Relay.
1	521	None	613
	506	321	625
2	521	None	613

85

90

In the case of keys 4 and 5 the connection of ground to conductor 521 through resistance 322 serves to bring about the transfer from one register to the next as will be 95 pointed out hereinafter.

Should the "B" operator press one or more of the numerical keys before the lamp 303 is extinguished (which indicates that the sender has not yet been attached, at which time relay 305 will not be operated), relay 364 will operate in a circuit which may be traced from grounded battery over the inner left or outer right back contact of relay 305, through retardation coil 360 and 361 over the back contact of relay 362 or 363 over the contact of one or more of the numerical keys, through the winding of relay 364 to ground at the right front contact of relay 314. Relay 364 operated closes a circuit for relay 319 through its winding over the front contact of relay 364, left back contact of relay 316 to ground at the right front contact of relay 314. Relay 319 locks over its left front contact to its energizing circuit independent of relay 364 and closes a circuit for lamp 303 over its right front contact, to ground through interrupter 341. When the sender is attached the sender indicator lamp 303 will be extinguished as explained hereinabove.

Relay 803 when operated as previously described closed a circuit extending from battery, through the winding of relay 813, left back contact of relay 826, conductor 834, to grounded conductor 610. Relay 813 operates and closes an obvious circuit for relay 814.

Assuming that the wanted number is 2603 the "B" operator will first depress numeri- 130

cal key 2 representing the first digit of the called number, relays 883 and 613 will operate in series in a circuit which may be traced from grounded battery, conductor 512, through the winding of relay 613, outer right front contact of relay 600, conductor 620, winding of relay 883, right front contact of relay 802, conductor 418, contact and brush 427 of the sender selector, conductor 419, inner right front contact of relay 517, conductor 554, brush and contact 553 of the position selector, conductor 521, inner left front contact of relay 305, retardation coil 361, back contact of relay 362, through the right closed contact of operated key 2, conductor 325, right front contact of relay 305, to ground at the right front contact of relay 314. Since direct ground was connected to the circuit of relay 613 by key 2, relay 613 will operate and lock in a circuit from battery over the inner right back contact of relay 809, conductor 632, inner right front contact of relay 600, left winding of relay 613, inner left front contact of relay 613 to ground. Relay 883 operated, operates relay 614 in a circuit which may be traced from grounded battery through the winding of relay 614, left outer front contact of relay 600, conductor 621 to ground at the right outer front contact of relay 883. Relay 614 operated, locks over its inner right contact, winding of relay 603, conductor 609 and grounded conductor 610. Relay 603 does not operate, being shunted by the operating circuit for relay 614. Relay 614 also closes a circuit for operating relays 619, 812 and 816. This circuit may be traced from grounded battery through the right back contact of relay 826, left winding of relay 812, inner left back contact of relay 817, conductor 622, left front contact of relay 614, conductor 623, right back contact of relay 625, right front contact of relay 613, winding of relay 619, conductor 626, through the winding of relay 816, outer left back contact of relay 818, conductor 885, front contact of relay 814, to ground over conductor 834. Relay 812 locks in a circuit from battery at the right back contact of relay 826, right winding and inner right armature of relay 812 to grounded conductor 834. Relays 619, 812 and 816 are employed in establishing the connection and will be discussed hereinafter.

When numerical key 2 is released by the "B" operator, relay 603 operates in the locking circuit of relay 614 since the release of key 2 permits relay 883 to release.

The operation of relay 603 opens the energizing circuit for relay 600 whereupon relay 600 releases. Relay 603 operated, operates relay 700 in a circuit which may be traced from grounded battery through the winding of relay 700, conductor 627, outer left front contact of relay 603,

outer left back contacts of relays 604, 605, 606 and 608 to grounded conductor 609. The operation of relay 700 places the sender circuit in position to receive registration on the second set of register relays. It may be noted that with relay 614 operated the locking circuit of relay 613 extends from ground over the inner left front contact of that relay over the left front contact and left winding of that relay, outer right front contact of relay 614 to battery over conductor 632 maintaining the locking circuit after relay 600 releases.

When numerical key 6 is depressed representing the second digit of the called number, relay 712 will energize in a circuit which may be traced from grounded battery over conductor 612, through the right windings of relays 770 and 712, inner right contact of relay 700, contact of relay 608, conductor 423, brush 428 of the sender selector, conductor 420, through the winding of relay 555, outer right front contact of relay 517, through brush and contact 556 of the position selector conductor 506, right front contact of relay 306, conductor 328, through the contact of operated key 6, conductor 329, through resistance 321, conductor 325 to ground at conductor 325. Relay 770 does not operate in this circuit due to the presence of resistance 321 in the circuit. Relay 712 locks in a circuit from battery on conductor 632, through the inner left front contact of relay 700, left winding and inner left front contact of relay 712 to ground.

The operation of key 6 also closes a circuit from grounded conductor 325 over the right contact of key 6, back contact of relay 363, through retardation coil 360, outer left front contact of relay 305, conductor 522, brush 558, of the position selector, inner left front contact of relay 517, conductor 461, brush 429 of the sender selector, conductor 424, winding of relay 884, conductor 620, outer right front contact of relay 700, right winding of relay 711 to battery over conductor 612. Relays 884 and 711 both operate. Relay 711 locks in a circuit from battery on conductor 632, inner left front contact of relay 700, left winding and inner left front contact of relay 711 to ground. Relay 884 closes a circuit from battery on conductor 632, over the inner left front contact of relay 700, winding of relay 701, conductor 707, middle left front contact of relay 700, conductor 628, outer right front contact of relay 884 to ground. Relay 701 locks over its left front contact to ground. Relay 884 in operating also closes a circuit from battery through the winding of relay 615, conductor 629, outer left front contact of relay 700, inner right front contact of relay 884 to ground.

Relay 615 locks in a circuit over its right contact, winding of relay 604, to grounded

conductor 609. Relay 604 does not operate in this circuit being shunted by the operating ground for relay 615.

When numerical key 6 is released by the "B" operator relay 604 operates in series with relay 615. The operation of relay 604 opens the energizing circuit for relay 700 at its outer left back contact whereupon relay 700 releases. Relay 604 operated also closes an energizing circuit for relay 702 which may be traced from grounded battery through the winding of relay 702, conductor 630, outer left front contact of relay 604, through the outer left back contacts of relays 605, 606 and 608 to grounded conductor 609. The operation of relay 702 places the sender circuit in position to receive registration upon the third set of register relays.

When the numerical key 0 is pressed by the "B" operator, relay 772 will operate in a circuit which may be traced from grounded battery, on conductor 612, right windings of relays 772 and 703, inner right front contact of relay 702, conductor 631, inner right back contact of relay 608, conductor 423, contact and brush 428 of the sender selector, conductor 420, winding of relay 555, outer right contact of relay 517, conductor 557, brush and contact 556 of the position selector, conductor 506, right front contact of relay 306, conductor 328, right contact of operated numerical key 0, resistance 321, conductor 325 to ground. Relay 703 will not operate in this circuit due to the presence therein of resistance 321. Relay 722 locks in a similar circuit to that of relay 613. Relay 884 will operate in a circuit which may be traced from grounded battery on conductor 612, right winding of relay 771, outer right contact of relay 702, conductor 620, winding of relay 884, conductor 424, contact and brush 429 of the sender selector, conductor 461, inner left front contact of relay 517, brush and contact 558 of the position selector, conductor 522, outer left front contact of relay 305, retardation coil 360, back contact of relay 363, conductor 330, to the left contact of operated numerical key 0, through resistance 322, conductor 325 to ground. Relay 771 will not operate in this circuit due to the series resistance 322.

Relay 884 closes a circuit from battery on conductor 632, inner left contact of relay 702, winding of relay 719, middle left contact of relay 702, conductor 628 to ground at the outer contact of relay 884. Relay 719 locks over its left armature to ground.

Relay 616 operates in a circuit which may be traced from grounded battery through the winding of relay 616, conductor 633, outer left front contact of relay 702, conductor 621 to ground at the inner contact of relay 884. Relay 616 locks through the winding of relay 605, to ground conductor 609.

When the "B" operator releases numeri-

cal key 0, relay 605 operates in series with relay 616. The operation of relay 605 opens the energizing circuit of relay 702 at its outer left back contact, whereupon relay 702 releases. Relay 605 operated causes relay 705 to operate in a circuit which may be traced from grounded battery through the winding of relay 705, conductor 634, outer left front contact of relay 605, outer left back contacts of relays 606 and 608 to ground at the left front contact of relay 803 in a circuit similar to that traced in the operation of relays 700 and 702. The operation of relay 705 places the sender circuit in position to receive registration on the fourth set of register relays.

When the numerical key 3 representing the fourth and last digit of the called number is pressed by the "B" operator, relays 773 and 774 operate in series in a circuit which may be traced from grounded battery, on conductor 612, through right windings of relays 774 and 773, inner right contact of relay 705, conductor 635, conductor 631, inner right back contact of relay 608, conductor 423, contact and brush 428 of the sender selector, conductor 420, winding of relay 555, outer right front contact of relay 517, conductor 557, brush and contact 556 of the position selector, conductor 506, right front contact of relay 306, conductor 328, through contact of operated numerical key 3, conductor 325 to ground at the right front contact of relay 314. Relays 773 and 774 lock in a similar circuit to the locking circuit of relay 613.

A circuit is also closed from battery on conductor 612, through the right winding of relay 775, outer right contact of relay 705, conductor 620, winding of relay 883, right front contact of relay 802, conductor 418, contact and brush 427 of the sender selector, conductor 419, inner right front contact of relay 517, conductor 554, contact and brush 553 of the position selector, conductor 521, inner left front contact of relay 305, retardation coil 361, inner back contact of relay 362, right closed contact of numerical key 3 to ground over conductor 325. Relays 775 and 883 both operate in this circuit, relay 775 locking to ground over its inner left front contact. Relay 617 operates in a circuit which may be traced from grounded battery through the winding of that relay, conductor 636, outermost left front contact of relay 705 to ground at the outer right front contact of relay 883. Relay 617 locks in a circuit over its right contact, winding of relay 606 to grounded conductor 609.

When numerical key 3 is released by the "B" operator, relay 606 operates in series with relay 617. The energizing circuit of relay 705 is opened by the operation of relay 606, whereupon relay 705 releases. The operation of relay 606 closes a circuit for

operating relay 608 which may be traced from grounded battery, inner left front contact of relay 606, left back contact of relay 607, through the winding of relay 608 to 5 grounded conductor 609. The operation of relay 608 will connect ground to conductor 423 through its inner right front contact and disconnect the "B" operator from the link circuit as will be hereinafter described.

10 As has been explained, the setting up of the first digit by the "B" operator, operates one of the relays 670, 619, 671, 672 or 673. These relays are provided with one or more armatures which, if the corresponding first 15 digit represents a group requiring five digits, are connected to grounded conductor 610. Relays 670, 619, 671, 672 and 673 operate individually when the register relays 613, 625 and 624 are operated in different 20 combinations and in cooperation with the register relay 646 are effective to operate the relay 607 to indicate that a five digit number is to be recorded. For example, if the first 25 digit registered is either two or seven, relay 619 is operated. If the digit is two and it is desired to record five digits for connections to all offices of the exchange designated by numbers whose first digit is two then the right armature of relay 619 is connected 30 to conductor 610 for operating relay 607 and all the other armatures of this group of relays would remain unconnected. If, however, the digit is seven and it is desired to record five digits the left armature of relay 35 619 is connected to conductor 610 and since for recording the digit seven, relay 646 is also operated the circuit of relay 607 will be prepared. Thus the right armatures of relays 619, 671, 672, 673 and 670, if connected, 40 will cause the operation of relay 607, if the first digit recorded is either two, three, four, five or six respectively, and the left armatures of relays 619, 671 and 672, if connected, 45 will cause the operation of relay 607, if the first digit recorded is either seven, eight or nine respectively. In the drawing it will be noted that the left armature only of relay 672 is shown connected and thus a five digit number is recorded only when 50 the first digit recorded is nine. The operation of a relay whose armature is grounded, therefore indicates to the sender that the complete number of digits is to be five, whereas the operation of any other relay indicates that the complete number of digits 55 to be set up will be four. The conversion of the four digit sender to a five digit sender is therefore effected by the operation of relay 607 due to the operation of the first digit relays having a grounded armature. The circuit of relay 607 may be traced from grounded battery through the winding of relay 607, conductor 639 to ground at the contact of the relay which corresponds 60 to the group reserved as five digit numbers.

The operation of relay 607 transfers the control of relay 608, which as has been previously noted, initiates the disconnection of the "B" operator's position from the fourth digit, relay 617, to the fifth digit relay 618. 70 The disconnection of the "B" position is therefore delayed until after the reception of the fifth digit.

Control of switching operation.

75

It will be remembered that the registration of the first digit caused the operation of relays 812 and 816 in the circuit of relay 619 and that relay 812 locked to grounded conductor 834. 80

The operation of relay 604 following the registration of the second digit closes a circuit for relay 824 which may be traced from grounded battery through winding of relay 824, outer right back contact of relay 825, 85 outer left back contact of relay 821, left front contact of relay 812, conductor 644, inner left front contacts of relays 603 and 604, conductor 643, contact of interrupter 822 to ground. Relay 824 operated, closes 90 an operating path for relay 825 and a locking path for itself which may be traced from grounded battery through the windings of relays 824 and 825 in series, right front contact of relay 824 to ground at the 95 inner left back contact of relay 821 to grounded conductor 610. Relay 825 operated, removes the shunt around interrupter 823. Relays 824 and 825 are operated so as to insure against part of a pulse being sent 100 out to the step-by-step switches over the leads 425 and 426. The removal of the shunt by the operation of relay 825 prepares 105 for the operation of the switches in accordance with interruptions controlled by the counting relays.

The circuit for operating first selector 150 was completed when relay 410 operated and may be traced from battery, right winding of relay 151, middle left back contact of 110 relay 152, conductor 153, through the trunk finder, contact of relay 213, conductor 234, middle right front contact of relay 410, conductor 421, brush and contact of the sender selector, conductor 425, winding of relay 115 881, outer right contact of relay 809, contact of interrupter 823, conductor 426, brush and contact of the sender selector, conductor 422, inner right contact of relay 410, inner right contact of relay 401, conductor 233, 120 uppermost contact of relay 213, through the trunk finder, conductor 154, outer left back contact of relay 152, left winding of relay 151, to ground at contact of relay 155 at the first selector. Relay 151 operates and closes 125 an obvious circuit for relay 156. Relay 156 prepares an operating circuit for vertical magnet 157 which may be traced from battery through the winding of magnet 157, winding of relay 158, inner front contact of 130

relay 156, to the back contact of relay 151.

In the sending out of pulses for the first digit set up (2), counting relays 819 and 820 and corresponding relays 818 and 821 are

- 5 operated to control the number of interruptions of the switches operating the circuit. Relay 819 operates in a circuit which may be traced from grounded battery through the winding of relay 819, inner left front contact of relay 816, inner left back contact of relay 818, outer right contact of relay 825, outer left back contact of relay 821, right front contact of relay 812, conductor 644, inner left front contacts of relays 604 and 603, 10 conductor 643, contact of interrupter 822 to ground. Relay 819 operated, closes a locking circuit for itself in series with relay 818 which may be traced from grounded battery through the winding of relay 819, front 15 contact of relay 819, winding of relay 818, outer left back contact of relay 817, conductor 885, front contact of relay 814 to ground. When interrupter 822 opens its contact relay 818 operates in this 20 circuit and opens the energizing circuit for relays 816 and 619 which release. Relay 812 does not release at this time as it is locked through its right winding and inner right front contact to grounded conductor 834. When interrupter 822 is closed the contact of interrupter 823 opens. Therefore the circuit of relay 151 is interrupted each time that a pair of counting relays is 25 operated.

- 30 Upon the second closure of the contact of interrupter 822, counting relay 820 will operate in a circuit which may be traced from grounded battery, through the winding of relay 820, right back contact of relay 827, inner left front contact of relay 818, outer right front contact of relay 825, and thence as traced for relay 819 to the closed contact of interrupter 822. Relay 820 operated, locks 35 in a circuit which may be traced from grounded battery through the winding of relay 820, front contact of relay 820, winding of relay 821 to grounded conductor 885. Relay 821 operated, releases relays 824 and 40 825 by opening its inner left back contact. The release of relay 825 will reclose the shunt around interrupter 823 and thus prevent the further interrupting of the circuit of relay 151.

- 45 At the first opening of the contact of interrupter 823, relay 151 releases completing the circuit above traced for magnet 157, to ground at its back contact. The operation of magnet 157 advances the first selector one vertical step, the second interruption of the circuit of relay 151 by interrupter 823 causes the advance of the first selector in a second vertical step. Relay 158 operates in the circuit of magnet 157 and being slow to release remains operated as long as the cir-

50 cuit to relay 151 is being interrupted. The operation of relay 158 closes a circuit from battery through the winding of relay 159, off-normal contact 160, front contact of relay 158, outer front contact of relay 156 to ground. Relay 159 locks in a circuit from battery through its winding, off-normal contact 160, back contact of magnet 161, right front contact of relay 159, inner left back contact of relay 152 to ground. When the 55 release of relay 825 closes the shunt around interrupter 823, relay 151 remains operated long enough to permit relay 158 to release. The release of relay 158 closes a circuit from battery, through the winding of rotary magnet 161, left front contact of relay 159, normal contact of relay 158, outer front contact of relay 156 to ground. Magnet 161 operates and advances the switch one rotary step into engagement with the first outgoing 60 trunk. If this trunk is busy, ground will appear on the sleeve terminal engaged by brush 162. As soon as magnet 161 closes its back contact relay 159 will be reoperated in a circuit extending through its winding, off-normal contact 160, back contact of magnet 161, right back contact of relay 152, sleeve brush 162 to ground. The operation of relay 159 65 will reclose the operating circuit for rotary magnet 161 and the switch will take another 70 rotary step. The operation of magnet 161 opens the circuit of relay 159. As long as sleeve brush 162 encounters ground, relay 159 will be reoperated after each rotary step 75 and the switch advances. A second circuit 80 for relay 159 also exists which may be traced through its winding, off-normal contact 160, back contact of magnet 161, winding of relay 152, contact 163 to ground at the outer 85 front contact of relay 156. As long as sleeve brush 162 encounters ground, relay 152 is shunted and does not operate. As 90 soon as an idle trunk is found characterized by the absence of ground, relay 152 operates. Relay 159 being marginal does not operate 95 in this circuit. The operation of relay 152 100 extends the tip, ring and sleeve conductors through to the next selector. It also opens the circuit of line relay 151 which relay releases in turn releasing relay 156. However, relay 156 holds its armatures attracted 105 for a time, thus maintaining ground on the sleeve conductor until the line relay and corresponding slow-to-release relay of the next 110 selector have operated to render both selectors busy.

The ground over sleeve brush 162 completes a locking circuit for relay 152 which may be traced from battery, through the winding of relay 159, off-normal contact 160, back contact of magnet 161, winding of relay 152, contact 163, front contact of relay 152, brush 162 to ground.

The operation of relay 821, as previously described, closes the circuit of relay 826

which may be traced from grounded battery, through the winding of that relay over the inner left front contact of relay 821 to grounded conductor 834. Relay 826 opens the energizing circuit for relay 813 at its left back contact. Relay 813 in turn releases relay 814. Relay 826 also removes battery from the energizing circuit of relay 812 which releases. The release of relay 814, releases counting relays 818 and 819, 820 and 821. Relays 603 and 614 release due to the operation of relay 826 which places battery on conductor 640. The release of relay 821 opens the energizing circuit for relay 826 at its left front contact. Relay 613 releases when relay 614 releases due to the opening of the locking circuit of the latter relay at the outer right front contact of relay 614. At the close of any digit, therefore, the operation of relay 826 releases the various register relays, and relays 812 and 814 are released and again operated to provide an interval for the purpose of allowing time for the switches to trunk hunt. When relay 826 releases, relay 813 operates again in a circuit similar to that previously traced. Relay 814 will accordingly reoperate.

It will be remembered that the second digit set up was 6. Under this condition register relays 701, 711 and 712 were operated. Relay 827 therefore energized as soon as relay 603 released in a circuit which may be traced from grounded battery, through the winding of that relay, back contact of relay 817, conductor 654, through the right front contact of relay 701, conductor 645 to ground at the outer right back contact of relay 603. The operation of relay 827 whenever the digit is greater than 5 alters the sequence of the counting relays to cause their repeated operation to count more than five interruptions of the switch control circuit. The counting for sending out the second digit (6) will start at counting relay 818 which operates in a circuit which may be traced from ground on conductor 834, front contact of relay 814, conductor 885, outer left back contact of relay 817, through the winding of relay 818, conductor 647, outer right back contacts of relay 770, right front contact of relay 711, outer left front contact of relay 712, conductor 648, outer left front contact of relay 615, right back contact of relay 614, conductor 622, inner left back contact of relay 817, left winding of relay 812, to battery at the right back contact of relay 826. Upon the closure of the contact of interrupter 822 with relay 818 operated, an energizing circuit is closed for relay 828. At the same time the first opening of interrupter contact 823 causes the second selector (not shown) to take a vertical step. The energizing circuit for relay 828 may be traced from grounded battery,

through the winding of that relay, inner right front contact of relay 827, inner left front contact of relay 818, outer right front contact of operated relay 825 over the circuit previously traced to the closed contact of interrupter 822.

Relay 828 operated will lock through its left front contact in series with the winding of relay 817, outer right front contact of relay 812 to grounded conductor 834. Relay 817 will operate in this circuit when interrupter 822 opens and open the energizing circuit for relay 827 at its right back contact, whereupon relay 827 releases. The operation of relay 817 also opens the energizing circuit for relay 818 which releases. Relay 829 then operates in a circuit which may be traced from grounded battery, through the winding of that relay, left back contact of relay 839, inner left back contacts of relays 830, 816 and 818, outer right front contact of relay 825 and thence to the closed contact of interrupter 822. Thus the second of the six pulses of the second digit will be counted.

Relay 829 operated, locks through its left front contact in series with the winding of relay 839 in a circuit similar to that traced for relay 819, relay 839 operating when interrupter 822 removes the operating ground from relay 829. Upon the third closure of interrupter 822 with relay 839 operated, counting relay 832 will operate in a circuit similar to that traced for counting relay 819. This will complete the counting of the third pulse to the second selector.

Relay 832 operated, will close a locking circuit for itself through its left front contact in series with the winding of relay 830, which latter relay operates. The operation of relay 830 will open the energizing circuit for relay 839 and the locking circuit for relay 829, whereupon these two relays release. The operation of relay 830 closes an energizing path for relay 833 at its inner left front contact and relay 833 operates upon the fourth closure of the contact of interrupter 822, counting the fourth pulse of the second digit 6.

Relay 833 operated will close a locking circuit for itself through its left front contact in series with relay 816 which relay operates. The operation of relay 816 will open the energizing circuit of relay 830 and the locking circuit for relay 832, whereupon these two relays will release. Upon the fifth closure of the contact of interrupter 822, relay 819 will operate counting the fifth pulse to the switch.

Relay 819 operated, will close a locking path for itself through its front contact in series with the winding of relay 818 which later operates. The operation of relay 818 opens the energizing path for relay 816 and

the locking path for relay 833, releasing these two last named relays. Upon the sixth closure of the contact of interrupter 822, counting relay 820 will operate and lock through its left front contact in series with the winding of relay 821 which relay operates. This will count the sixth and last pulse of the second digit set up, namely 6.

The operation of relay 821 releases relays 824 and 825. The release of relay 825 replaces the shunt around interrupter 823 which prevents the further interruption of the switch control circuit. The operation of relay 821 operates relay 826, the operation of which releases relays 813 and 814. Relays 615 and 604 will also release.

The third digit zero will be marked on the counting relays to determine at which point the operation of the counting relays will begin in a manner similar to that described for the second digit. Relay 827 will at first be operated (the third digit also being a number above 5) whereupon the following pairs of counting relays will be operated to count 10 pulses: 829—839, 832—830, 833—816, 819—818, 828—817, 829—839 (operated for the second time), 832—830, 833—816, 819—818, 820—821. At the close of the digit the operation of relay 821 causes sending to cease by the operation of relay 826. The various register relays are caused to release as described hereinabove.

The fourth digit 3 will be marked on the counting relays, the operation of the counting relays beginning at relay 830. Relays 833—816, 819—818, 820—821 are subsequently operated in the course of sending out three pulses. Following the completion of the last digit, relay 608 releases initiating the release of the sender as will be herein-after described.

The operation of the switches for extending the connection from the first selector to the called subscriber will take place in the usual way and the subscriber will be signaled.

Release of the position.

When the "B" operator releases the key corresponding to the last digit of the number received from the "A" operator, and relay 608 operates as previously described a circuit is closed from battery through the winding of relay 335, back contact of relay 362, conductor 328, right front contact of relay 306, conductor 506, brush and contact 556 of the position selector, outer right front contact of relay 517, winding of relay 555, conductor 420, brush and contact 428 of the sender selector, conductor 423, inner right front contact of relay 608 to ground. Relay 555 operates in this circuit in turn operating relay 549 by connecting ground to the winding of relay 549 over its right front

contact. Relay 549 operated, opens the ground to relay 542 at its outer left back contact, thus opening the original energizing circuit for relay 542 and starting the release of the position. Relay 549 operated, operates relay 406 in a circuit which may be traced from grounded battery, through the winding of relay 406, inner left front contact of relay 549, conductors 559, 545, 408 and 412 to ground at the middle front contact of relay 403. Relay 406 operated, locks through its inner right front contact and closes a shunt around relay 517 which circuit may be traced from battery through the winding of relay 511, outer right front contact of relay 406, right back contact of relay 542 to grounded conductor 408. This circuit holds relay 511 operated and releases relay 517. The release of relay 517 opens the conductors connecting the sender and the position. Relay 406 in operating removes ground from the test brush 527 of the position selector. It also opens the energizing circuit of relay 510, whereupon relay 510 releases to disconnect the position from the conductors incoming from the "A" operator. Relay 406 also closes a holding circuit for relay 555 at its outermost left front contact. The operation of relay 549 also opens the circuit of relay 300 so that that relay releases in turn releasing relay 301. The release of relay 301 closes a circuit from battery through lamp 302, inner right front contact of relay 352, outer right back contact of relay 301, interrupter 341 to ground. Lamp 302 flashes in this circuit until the operation of relay 406 removes ground from conductor 507. The removal of ground from conductor 507 permits the release of relay 314 which removes ground from conductor 325; opens the locking circuit of relays 306 and 319; opens the holding circuit of relay 305; and opens the energizing circuit of relay 354. Relay 354 in turn releases relay 353 which opens the circuit of relay 355 and in turn the circuit of relay 356. The "B" operator's position is now free to care for calls incoming on other link circuits.

It will be clear from the foregoing description that as soon as the operator has finished setting up a number the sender will indicate to the link that the operation of the position has been completed and will bring about the disconnection of the link from the position after which the position is free to be seized by another link.

Release of the sender.

When the sender finishes controlling the establishment of the connection, relay 608 releases, opening the circuit of relay 555 which releases in turn and opens the energizing circuit for relay 549. Relay 549 re-

leasing, connects ground from conductor 408, inner right front contact of relay 406, over the inner left back contact of relay 549, conductor 430, and the front contact of relay 5 431 to cut-through conductor 238 of the trunk. The release of relay 549 opens the holding circuit of relay 202 and that relay releases disconnecting ground from conductor 236 and releasing relay 403. The release 10 of relay 403 opens the locking circuit for relay 406 and the holding circuit of relay 511. The release of relay 202 also opens the circuit of relay 213 which in turn opens the pulsing leads connecting the sender and the 15 switches. The opening of these conductors permits relay 881 to release. Relay 882 is thereupon released in turn releasing relay 203. The release of relay 803 removes battery and ground from the control conductors 20 of the sender and in turn releases relay 807. Relay 807 releases relay 802. The sender is now in condition to serve another call.

Cut through of connection.

25 The connection of ground to conductor 238 as above described completes a circuit which extends from conductor 238 over brush 239, contact 121, conductor 122, through the winding of relay 114 to battery. Relay 114 operates and locks to ground on sleeve conductor 123 under the control of the called subscriber. The operation of relay 114 connects the trunk through the connecting switches to the called subscriber and opens test lead 117 to the trunk finder circuit. This permits relay 109 to release and reconnect the relay 107 to the trunk. Relay 107 operates and in turn operates relay 108 as before. The operation of relay 108 completes the closure of the loop 40 of the called subscriber which was partially closed by the operation of relay 114. When the called subscriber answers, battery is reversed over the tip and ring conductors in the usual manner causing the operation of relay 125. Relay 125 closes an obvious circuit for relay 110 which reverses the connection of battery to the "A" operator's position and operates a signal there.

Restoration of the link.

50 The release of relay 202 as above described opens the circuit of relay 213 and that relay releases. Relay 202 being slow to release a shunting path is momentarily closed across conductors 204 and 205 to provide a path for quickly operating relay 107. The release of relay 213 opens the circuit of relay 431 and that relay releases in turn releasing relays 400 and 401. The release of relay 213 55 also opens the locking circuit of relay 210 of the link circuit. When both relays 213 and 202 release, a circuit is closed from battery through winding of release magnet 214, off-normal contact 280, lower back contact of relay 213, middle left back contact of relay 60

202 to ground. The operation of release magnet 214 restores the trunk finder to normal and the link is now ready to serve other calls.

Restoration of the trunk.

70

When the calling subscriber restores the receiver the usual supervisory signal is given to the "A" operator. When the called subscriber hangs up relay 125 is released in turn 75 releasing relay 110. The release of relay 110 again reverses the battery connected to the incoming end of the trunk giving an indication to the "A" operator that the conversation is ended. The removal of plug 112 from jack 104 releases relay 107 in turn releasing relay 108. The release of relay 108 opens the tip and ring conductors, permitting the release of the connector, and in turn the switches of the train used in establishing the connection. The release of the connector removes ground from the release conductor, which is connected to terminal 150. Relay 152 thereupon releases and closes a circuit from ground over its inner left back contact, 80 back contact of relay 151, back contact of relay 156, off normal contact 165, winding of release magnet 166 to battery. The operation of release magnet 166 restores the first selector to normal. The removal of ground from brush 162 also opens the locking circuit 85 of relay 114 and that relay releases.

Use of sender with 5 digit numbers.

90 As was previously pointed out, the transformation of the sender from one handling 4 digits to one handling 5 is brought about by the operation of relay 607. The circuit of relay 607 in the present case extends through the winding of that relay over the outer left front contact of relay 646, left front contact of relay 672 to grounded conductor 609. These two relays are operated 95 when the first digit register is set. Accordingly whenever a 5 place number beginning 100 with the digit 7 is set up by the "B" operator, relay 607 will be operated as soon as the first digit is registered. From the previous description of the operation of the sender 105 it will be remembered that relay 603 operated after the registration of the first digit, relay 604 after the registration of the second digit, relay 605 after the registration of the third digit, and relay 606 after the registration of the fourth digit. With relay 607 110 normal, the operation of relay 606 closes a circuit for the operation of relay 608 which initiates the release of the position as previously described. With relay 607 operated 115 this circuit is opened at the left armature of relay 607 and the connection between the position and the sender is maintained as a fifth digit is registered. During the registration 120 of the fifth digit, relay 618 is operated 125 through the front contact of relay 708 in a 130

manner similar to relay 614 and others. Relay 618 locks over its right front contact, left front contact of relay 607, winding of relay 608 to grounded conductor 609 whereupon 5 relay 608 causes the disconnection of the position as previously described. In setting up a connection, relays 603, 604, 605 and 606 are released following the sending out of the corresponding impulses as previously described. 10 Due to the operated condition of relay 607 the release of relay 606 does not open the circuit of relay 608 but does extend the releasing circuit through battery from the front contact of relay 608 to the winding of relay 618 so that relay 608 which is operated in the locking circuit of relay 618 does not release until the fifth set of pulses have been sent out.

20 *Sender reset.*

If in setting up a series of digits, the "B" operator finds that she has made a mistake but has not yet set up the last number of the digit to be set up, she can press her sender reset key 332 which will operate relay 316 in a circuit which may be traced from grounded battery, through the winding of relay 316, operator's sender reset key 332 to ground at the right front contact of relay 314. 25 Relay 316 operated, operates relays 333 and 318 in obvious circuits. Relay 318 operated, closes an obvious circuit for relay 370 which in turn connects direct ground to leads 522 and 521. Direct ground on conductor 521 causes the operation of relay 883 through the winding of relay 613, 711 or 771 and direct ground on conductor 522 causes the operation of relay 884 through the winding of one of the above mentioned relays. 30 The operation of both relays 883 and 884 closes a circuit from ground at the outer right contact of relay 884, inner right contact of relay 883, through the winding of relay 890 to battery operating that relay. The operation of relay 890 connects battery directly to the windings of relays 883 and 884 and connects ground over its inner right front contact to the winding of relay 809. 35 Relay 809 opens the locking ground for all the register relays and the relays of Fig. 8 restoring these relays to normal. It will be remembered that relays 802, 807 and 803 depend upon relay 882. The operation of relay 809 closes an alternate holding circuit for relay 882 over its left front contact to the right front contact of relay 803 and hence relays 802, 807, 803 and 882 are held operated. 40 However, the circuit of relay 881 and the pulsing circuit for controlling the switches is opened by the operation of relay 809 causing the restoration of any switches which may have been set. Relays 333 and 318 in the "B" operator's position circuit are slow to release and accordingly hold relay 370 operated an appreciable length of

time to make sure that relay 809 will be held operated for a sufficient time to allow the relays in the sender circuit which had been operated by the pressing of numerical keys to return to normal. As soon as this 50 time interval elapses, relay 807 will release and the sender will again be in position to register the digits sent out by the operator.

It will be clear from the foregoing description that the operation of the sender reset key has no effect on the link circuit so that the position link and sender remain operated and the operator is free to set up the new number as though no registration had been attempted.

55 *Disconnection by operator.*

Under normal conditions the link, sender and position circuits are disconnected as previously described. However, it is possible for either the "A" operator or the "B" operator to disconnect if she so desires. If the "A" operator desires to disconnect, she needs only to remove her cord circuit from the jack 104. This will release relay 431 which will 60 in turn release relays 401 and 400. The further release of the apparatus awaits the completion of the operation of the sender. At that time relay 114 is operated to connect the right windings of repeating coil 111 through to the called subscriber's line. Immediately thereafter relay 213 releases. The operation of relay 114 releases relay 109 to 65 permit the operation of relays 107 and 108 and the completion of the called subscriber's 70 circuit. However, since plug 112 has been withdrawn from jack 104, these relays cannot operate and the connector releases as soon as relay 213 releases, in turn releasing the rest of the connection.

75 If the "B" operator wishes to disconnect she may do so as soon as she finishes recording the number by operating the link disconnect key 337, in turn operating relay 353 to put ground on conductor 507 to mark the 80 position circuit as busy during release. This will also close a circuit from battery through the right winding of relay 542, outer left front contact of relay 510 and brush 552 of the position finder, conductor 514 to ground 85 over the contact of key 337. Relay 542 connects ground to both terminals of relay 517 which releases, opening the conductors connecting the position circuit to the sender. It also closes a circuit from the battery 90 through the left winding of relay 405 conductor 449, outer left front contact of relay 542 to grounded conductor 408. Relay 405 opens the holding circuit of relay 510 which disconnects the position from the trunk and 95 opens the circuit of relay 300 to release the position apparatus. Relay 542 also disconnects ground from conductor 507 freeing the 100 position for selection by other position finders. The operation of relay 405 will 105

nect relay 437 to interrupter 430. Relay 437 reverses the connection of relay 431 to the "A" operator's position to flash a lamp at that position.

5 *Stuck sender.*

If the sender does not complete its operation and release the link within a predetermined interval, means are provided for signaling the "A" operator who may then release the connection.

When relay 549 operated as previously described, a circuit was closed from battery, through the winding of relay 432, back contact of relay 433, inner right contact of relay 549, conductor 560 to the timing circuit where ground was momentarily connected to conductor 560. Relay 432 locks through winding of relay 433, contact of relay 432 to ground at the inner left contact of relay 403. Relay 433 operates when ground is disconnected from conductor 560. The operation of relay 433 closes a circuit from battery through the right winding of relay 405, front contact of relay 433, inner right contact of relay 549 to conductor 560. The timing circuit measures off an interval of several seconds predetermined in accordance with traffic conditions, whereupon ground is reconnected to conductor 560 and relay 405 operates and locks through its left winding and inner left front contact through conductor 408. The operation of relay 405 closes a circuit from battery, through winding of relay 437, inner right contact of relay 405, interrupter 436 to ground. Relay 437 is intermittently operated in this circuit to reverse battery over the trunk conductors to the "A" operator's position and flash her cord lamp, not shown, indicating to her that the sender is stuck. Under this condition the "A" operator will remove her cord from the jack 104 and relay 431 will release as previously described. The release of relay 401 opens the circuit of relay 202 and that relay releases disconnecting the link circuit from the trunk finder and restoring the trunk finder to normal. The release of relay 202 opens the circuit of relay 403 as previously described and that relay brings about the release of the rest of the link and the sender.

55 *Stuck link.*

If the link does not release within a predetermined interval, the "A" operator is signaled. The operation of relay 403 which initiates the operation of the position finder closes a circuit from battery to the winding of relay 445, back contact of relay 446, outer right front contact of relay 403, conductor 447 which also extends to the timing circuit where ground is momentarily connected to conductor 447. Relay 445 operates and locks through the winding of relay 446, front contact of relay 445 to ground at the inner left front contact of relay 403. Relay 446 closes a circuit from battery through the right winding of relay 442, front contact of relay 446, outer front contact of relay 443 to conductor 447. After an interval predetermined from traffic conditions, ground is connected to conductor 447 a second time and the above circuit for relay 442 completed. Relay 442 locks through its left winding and inner right front contact to grounded conductor 408. It operates stuck link pilot lamp 444 in an obvious circuit. This lamp appears at the "A" operator's position and that operator may release the link in the manner previously described.

5 *Stuck link key.*

If there have been complaints of stuck sender conditions or other reasons to suspect stuck link or stuck sender trouble, the operation of stuck link key 438 will prevent the release of the sender and link when the "A" operator disconnects and will enable the trouble man to locate the sender or link which has been giving trouble. With key 438 operated, when the "A" operator releases the link and sender after they have become stuck, relay 439 operates in a circuit from battery, through its winding, upper contact of key 438, back contact of relay 401, lower contact of key 438, outer left front contact of relay 405 to grounded conductor 408, if the sender has become stuck or over the inner left front contact of relay 442, to grounded conductor 408 provided it is the link circuit which has been stuck. Relay 439 closes a locking circuit for itself over the upper contact of key 438 and its two inner armatures to ground. This ground also serves as a locking circuit for relays 442 and 405 so that they do not release when relay 403 releases due to the opening of the holding circuit of relay 202. If relay 442 has not operated, relay 405 and key 438 operated will close a circuit from battery through the left winding of relay 442, lower contact of key 438, outer left front contact of relay 405 to grounded conductor 408, causing the operation of that relay. Relay 442 operated, lights stuck link pilot lamp 444. The locking of relays 442 and 405 prevents the release of the sender and link circuit until the attendant releases key 438 having identified the circuit and possibly having corrected the difficulty.

It will be remembered that when relay 511 operated relay 520 was operated and locked. The purpose of relay 520 is to prevent a link from seizing an operator's position if it has once seized an operator and been released while other calls are waiting to be served. Therefore, in a group of

links as each link is served, it will be locked out providing a call is still waiting on another link. When all links have been served, those links on which a call is waiting will be free and may then select an operator. Relay 520 is individual to the link circuit while relay 546 is common to the group of link circuits. The operation of relay 520 closes a circuit over its inner left front contact through the winding of relay 546 to battery through resistance 565. However, relay 510 was operated before relay 520 and therefore a circuit is closed from battery, through resistance 565, over the left back contact of relay 546, inner left front contact of relay 510 to ground at the left back contact of relay 410, in shunt of relay 546, until relay 410 operates to connect the pulsing leads to the sender at which time it also opens the energizing circuit of relay 520. If no other link circuit is waiting at this time, relay 546 operates, opening the locking circuit of relay 520.

If, however, the operation of another link circuit in the group has been started, the relay 403 of that link will have operated and a circuit will be closed from ground at the outer left front contact of that relay, over the left back contacts of the relays 509 and 520 of that link to the back contact of relay 546 shunting that relay and preventing the release of relay 520 of the link shown. The presence of additional links awaiting an operator would prevent the release of the relays 520 of the remaining links that had been served.

When a locked out link is selected a second time, the operated condition of relay 520 opens the circuit of the relay 500 and prevents the operation of the position finder. It also prevents the closure of the shunt around relay 546 by that link. When all the waiting links have found an operator, the shunts will be removed from relay 546 and the relays 520 will release. Immediately after they release the corresponding shunt circuit from relay 403 will be extended to relay 546 to delay second calls on links already served once.

50 *All "B" positions busy.*

As each position is taken for use, the relay 301 of that position removes the ground from conductor 352 which is connected thereto over the right back contact of relay 301 when the position is idle. As mentioned before, when the position is vacated the withdrawal of the headset plug releases relay 350 and disconnects ground from conductor 352. As long as an occupied position remains idle, the direct ground on conductor 352 shunts and prevents the operation of relay 528. When all occupied positions become busy the shunt is removed from relay 528 and that relay operates when the

next link circuit is taken for use to light lamp 535 as an indication that a call is waiting.

What is claimed is:

1. In a telephone system a selective switch, 70 a switch controlling circuit, means for transmitting impulses over said circuit to control said switch, and means for counting the impulses transmitted comprising a set of counting relays including optional pairs of relays 75 for a particular impulse of series of impulses the choice being dependent upon the number of impulses in a series.

2. In a telephone system a selective switch, 80 a switch controlling circuit, means for transmitting impulses over said circuit to control said switch, and means for counting the impulses transmitted comprising a set of counting relays employing a smaller number of pairs of relays than the maximum number 85 of impulses to be counted including optional pairs of counting relays for a particular impulse of series of impulses the choice being dependent upon the number of impulses in a series.

3. In a telephone system a selective switch, 90 a switch controlling circuit, means for transmitting impulses over said circuit to control said switch, and means for counting the impulses transmitted comprising a train of 95 counting relays including means to progressively operate and progressively release the relays of said train, means to use any number of relays in said train for counting a series of impulses, and means to mark the 100 first relay to be used for a series of impulses by the operation of the preceding counting relay.

4. In a telephone system a selective switch, 105 a switch controlling circuit, means for transmitting impulses over said circuit to control said switch, and means for counting the impulses transmitted comprising a train of counting relays employing a smaller number of pairs of relays than the number of impulses to be counted and including means to 110 progressively operate and progressively release the relays of said train, means to use any number of relays in said train for counting a series of impulses, means to mark the 115 first relay to be used for a series of impulses by the operation of the preceding counting relay and optional pairs of counting relays for a particular impulse of series of impulses the choice being dependent upon the number 120 of impulses in a series.

5. In a telephone exchange system, a selective switch, a switch controlling circuit, means for interrupting said circuit to operate said switch, means for rendering said interrupting means effective, means for counting the number of interruptions of said circuit comprising a series of pairs of counting relays, means for preparing the circuit of the first counting relay to be operated, means 130

for operating a pair of counting relays for each interruption of said circuit, means operative when the number of interruptions is greater than the number of pairs of counting 5 relays to substitute an additional pair of relays for a particular pair of the series, to cause a subsequent operation of the series of relays, and means under the control of said particular pair of counting relays for 10 rendering said interrupting means ineffective.

6. In a telephone system a selective switch, a switch controlling circuit, means for transmitting impulses over said circuit to control 15 said switch, and means for counting the impulses transmitted comprising a counting relay arrangement employing a smaller number of pairs of relays than the maximum number to be counted, means for starting 20 the counting relay operation with any pair of relays, means under the control of a particular relay to mark the end of counting and means operative when the number to be counted is greater than the number of pairs 25 of relays in the series to substitute an additional pair of relays for said particular pair in the series and to cause a subsequent operation of the series.

7. In a telephone system, a register sender 30 comprising a plurality of registers, means for setting the registers of said sender, means for associating said setting means with said sender, means normally operated after the setting of a predetermined number 35 of registers to disconnect said sender from said setting means, and means for delaying the disconnection of said sender from said setting means until after the setting of an additional register.

40 8. In a telephone exchange system, a register sender, means for setting the registers of said sender, switches to be set by said sender, means for associating said sender with said switches, means normally operated after the completion of a predetermined number 45 of switch setting operations to disconnect said sender from said switches, and means for delaying the disconnection of said sender from said switches until after 50 the completion of an additional switch setting operation.

55 9. In a telephone exchange system, a register sender comprising a plurality of registers, means for setting the registers of said sender, switches to be set by said sender, means for associating said setting means with said sender and said sender with said switches, means normally operated after the setting of a predetermined number 60 of registers to disconnect said sender from said setting means, means normally operated after a predetermined number of switch setting operations to disconnect said sender from said switches, means for delaying the

disconnection of said sender from said setting means until after the setting of an additional register and for delaying the disconnection of the sender from said switches until after the completion of an additional switch setting operation. 65 70

10. In a telephone system a register sender comprising a plurality of registers, means for setting the registers of said sender, means for associating said setting means with said sender, means normally operated 75 after the setting of a predetermined number of registers to disconnect said sender from said setting means, and means operative in accordance with the setting of the first register for delaying the disconnection 80 of said sender from said setting means until after the setting of an additional register.

11. In a telephone exchange system, a register sender, means for setting the registers of said sender in accordance with a plurality of digits, switches to be set by said sender, means for associating said sender with said switches, means normally operated after the completion of a predetermined number 85 of switch setting operations to disconnect said sender from said switches, and means operative in accordance with the first digit registered for delaying the disconnection of said sender from said switches until after the completion of an additional 90 switch setting operation.

12. In a telephone exchange system, a register sender comprising a plurality of registers, means for setting the registers of said sender, switches to be set by said sender, means for associating said setting means with said sender and said sender with said switches, means normally operated after the setting of a predetermined number of registers to disconnect said sender from said setting means, means normally operated after a predetermined number of switch setting operations to disconnect said sender from said switches, and means operative in accordance with the setting of the first register for delaying the disconnection of said sender from said setting means until after the setting of an additional register and for delaying the disconnection of the sender from said switches until after the completion of an additional switch setting operation. 100 110 115

13. In a telephone exchange system, an operator's position, a key set thereat, a register sender comprising a plurality of relay registers, means for associating said key set with said sender, means under the control of said key set for setting the registers of said sender, means in said sender operative when said registration is completed to disconnect said key set from said sender, and means under the control of said operator effective prior to the completion of said 120 125

registration to release said register relays without disconnecting said key set from said sender.

14. In a telephone exchange system, an operator's position, a key set thereat, a register sender comprising a plurality of relay registers, selector switches, means for associating said sender with said key set and with one of said selector switches, means under the control of said key set for setting the register of said sender, means in said sender operative when said registration is

completed to disconnect said key set from said sender, means under the control of said sender for starting the operation of said selector switches prior to the completion of registration, and means under the control of said operator effective prior to the completion of said registration to release said register relays and said switches. 15

In witness whereof, I hereunto subscribe my name this 15th day of October A. D., 1925.

BERT G. DUNHAM.
